(57) **CLAIM**

The ornamental design for a battery, as shown and described.

DESCRIPTION

FIG. 1 is a top and right front perspective view of a first embodiment of a battery, showing our design;
FIG. 2 is a front elevational view of the first embodiment;
FIG. 3 is a rear elevational view of the first embodiment;
FIG. 4 is a left side elevational view of the first embodiment;
FIG. 5 is a right side elevational view of the first embodiment;
FIG. 6 is a top plan view of the first embodiment, rotated ninety degrees clockwise; and,
FIG. 7 is a bottom plan view of the first embodiment, rotated ninety degrees counterclockwise.

The phantom lines shown in the figures of the first and third embodiments are shown for illustrative purposes only and form no part of the claimed design of their respective embodiment.

The design of the present application is directed to a battery that can be used, for example, in a camera or camcorder.

1 Claim, 3 Drawing Sheets
